(57) **CLAIM**

The ornamental design for an automotive floor right-front mat, as shown and described.

DESCRIPTION

FIG. 1 is a top, left and rear side perspective view of an automotive floor right-front mat, showing my new design; FIG. 2 is a bottom and rear side perspective view thereof; FIG. 3 is a top plan view thereof; and, FIG. 4 is a bottom plan view thereof.

The broken lines shown in the drawings illustrate portions of the automotive floor right-front mat that form no part of the claimed design.
